SEPARATION OF XYLENE

William F. Yates, Texas City, Tex., assignor to
 Monsanto Chemical Company, St. Louis, Mo.,
 a corporation of Delaware

No Drawing. Application May 26, 1950,
 Serial No. 164,620

7 Claims. (Cl. 260—674)

1

The present invention relates to hydrocarbon recovery, and deals more particularly with the separation of para-xylene from technical xylene fractions.

A great deal of effort has been directed to the provision of processes for the isolation of the isomeric xylenes from hydrocarbon fractions containing the same. Based on the fact that meta-xylene is more readily sulfonated than the other xylenes, a number of prior processes have employed sulfonation procedures, particularly for the recovery of meta-xylene.

The difference known to exist in the ease of hydrolysis of the various xylenesulfonic acids has also contributed to the frequent use of the sulfonation procedure.

Thus, in prior art, it was known that the partial sulfonation of a crude xylene fraction, e. g., by a moderately strong sulfuric acid under conditions preventing complete sulfonation would dissolve, or sulfonate, a predominance of the m-xylene content of the crude xylene. The other xylenes were believed to be either undissolved or only partially affected under the same conditions.

It was also known that xylenesulfonic acids can be fractionally hydrolyzed to the corresponding xylenes. For example, in a steam distillation hydrolysis, m-xlenesulfonic acid was found to hydrolyze at temperatures of from 125 to 150° C., paraxylenesulfonic acid at temperatures of from 150 to 170° C., and o-xlenesulfonic acid and ethylbenzenesulfonic acid at above 170° C.

Based on the above, there have been devised various methods for the separation of the individual xylenes as well as of the ethylbenzene present in technical xylene fractions. The xylene was first partially sulfonated, e. g., by treatment with a sulfuric acid, of say less than 95 per cent H₂SO₄ concentration, and the unsulfonated oil was separated, and submitted to complete sulfonation, i. e., treatment with a stronger sulfuric acid. Separation of the xylenes present in the two different sulfonic acid fractions thus obtained was then effected either by selective hydrolysis, fractional crystallization or a combination of the two procedures.

Depending upon the individual xylene isomer desired, the procedure generally outlined above has been somewhat varied. However, the prior art has not provided an industrially feasible

2

method for the substantially total recovery of a high-grade para-xylene and of a high-grade ethylbenzene from technical xylene mixtures.

An object of the present invention is to recover in good yields pure or substantially pure para-xylene from mixtures thereof with other xylenes. Another object of the invention is to recover pure or substantially pure ethylbenzene from technical xylene fractions containing ethylbenzene. Other objects will be hereinafter disclosed.

According to the invention, a recovery of para-xylene and, if desired, of ethylbenzene from crude xylene, i. e., xylene from commercial sources such as coal-tar, coke-oven distillates, petroleum tar oils, etc. is effected in better yields than have been previously attained on a technical scale by operating substantially as follows:

Crude xylene is distilled to remove a major portion of its ortho-xylene content to give a hydrocarbon fraction having a boiling point of approximately 130° C. to 145° C. and containing a predominance of meta-xylene, a lesser proportion of para-xylene and small amounts of ethylbenzene and ortho-xylene. This distilled product will be referred to hereinafter as technical xylene. This hydrocarbon fraction is submitted to partial sulfonation, the unsulfonated oil (a) is separated from the product and the sulfonated material (b) is subjected to fractional distillation hydrolysis. Foreruns (c) obtained by fractional distillation hydrolysis at temperatures of up to 120° C. are added to the unsulfonated material (a), intermediate material hydrolyzing at from 120° C. to 145° C. and comprising substantially m-xylene is separated, and hydrolysis product (d) obtained by hydrolyzing at above 145° C. is also added to the unsulfonated oil (a). The mixture of unsulfonated oil (a), hydrolysis foreruns (c) and hydrolysis product (d) is then completely sulfonated, e. g. by treatment with strong sulfuric acid, i. e., of above 95 per cent H₂SO₄ concentration. Distillation hydrolysis of the completely sulfonated material yields, at a temperature of from 150° C. to 170° C. a fraction containing a predominance of para-xylene and above 170° C. a fraction containing a predominance of ethylbenzene.

Briefly, the present process may be outlined as follows:

The above process differs essentially from prior methods employed for the separation of para-xylene and of ethylbenzene from technical xylene in that according to the present invention there is effected the repeated sulfonation of not only the unsulfonated oil (a), but also of the foreruns (c), and the hydrolysis product (d). Previously, it was generally believed that the foreruns (c) were of no importance in the recovery of individual xylenes; it being assumed that in the hydrolysis step material coming over at below 120° C. consisted essentially of water and paraffinic compounds. Also unappreciated were the advantages obtainable by a re-sulfonating the hydrolysis product (d) along with the unsulfonated oil (a). Contrary to previous practice, we have found that incorporation of the hitherto discarded foreruns (c) into the material which is to be re-sulfonated results in a substantially increased recovery of xylenes, particularly p-xylene, as well as of ethylbenzene. With respect to p-xylene, our investigations have shown that while re-sulfonation of only the unsulfonated oil (a) results in the recovery of but about 50 per cent of the p-xylene present in the xylene mixture, addition of the foreruns (c) to the unsulfonated oil (a), and complete sulfonation of the resulting mixture results in the recovery of about 70 per cent of the p-xylene. Addition to the unsulfonated oil (a) of not only the foreruns (c) but also the hydrolyzed product (d) results in the recovery of about 85 per cent of the p-xylene. The present process also permits substantially complete recovery of ethylbenzene from technical xylene mixtures.

The invention is further illustrated, but not limited, by the following example:

Example

A technical xylene fraction having a boiling point of 125° C. to 141.7° C. after removal of ortho-xylene was employed in this example. It had the following composition:

	Per cent
Ethylbenzene	6.3
o-Xylene	1.5
m-Xylene	63.5
p-Xylene	28.7

191.8 pounds of the above fraction was reacted with 85 per cent sulfuric acid for a time of 30

minutes at a temperature of from 80° C. to 85° C. The quantity of acid employed was 2.74 lbs. of 85 per cent H₂SO₄ per lb. of the fraction.

The unsulfonated oil (a) weighing 67.8 lbs. was separated from the reaction mixture, and the remaining sulfonic-sulfuric acid mixture was diluted with water and steam distilled to a temperature of 120° C. There was thus obtained 18 lbs. of the forerun (c), which was added to the unsulfonated oil (a). Further distillation of the remainder of the sulfonic-sulfuric acid mixture at a temperature of from 120° C. to 145° C. gave 90 lbs. of a fraction consisting predominantly of meta-xylene. Distillation of the residue at a temperature of over 145° C. gave 16 lbs. of a hydrolysis product (d), which was also added to the unsulfonated oil (a).

The 101.8 lbs. of the mixture of unsulfonated oil (a), forerun (c) and hydrolyzed product (d) were then sulfonated completely by reaction with 96 per cent sulfuric acid. The resulting sulfonic-sulfuric acid mixture was then diluted with water and the temperature of the diluted mixture was raised to 145° C. to 150° C. At this temperature there was obtained a fraction consisting essentially of 40.1 lbs. of meta-xylene. Distillation hydrolysis of the remainder at a temperature of from 150° C. to 170° C. yielded 49.7 lbs. of a fraction containing 44.9 lbs. (90.4 per cent) of para-xylene. At over 170° C. there was obtained 12 lbs. of a fraction consisting essentially of ethylbenzene.

The fraction distilling at 150° C. to 170° C. and consisting of 90.4 per cent para-xylene, 4.0 per cent of meta-xylene and 5.6 per cent of ortho-xylene may be used as such for many industrial purposes, or the para-xylene may be further concentrated by cooling the fraction to minus 12° C. whereby the para-xylene solidifies. Filtration of the solid para-xylene yields 40.1 lbs. of an approximately 98 per cent pure para-xylene.

The above procedure may be somewhat varied, particular with respect to the composition of the xylene fraction employed in the first sulfonation.

It has been found that in order to obtain para-xylene of at least 90 per cent purity, the ratio of ortho-xylene to para-xylene in the xylene fraction should not be greater than 1:20, and that the purity of the para-xylene increases with decreasing content of ortho-xylene in the material which is to be sulfonated. Thus, careful fractional distillation to give a fraction containing only from 0.2 to 0.3 per cent of ortho-xylene, instead of the fraction employed for the first sulfonation in the above example, may yield a para-xylene in the second distillation hydrolysis step of approximately 95 per cent purity. In this case further concentration by fractional crystallization will be unnecessary for most purposes.

The first sulfonating procedure may also be somewhat varied. The acid need not be of 85 per cent strength; however, the acid strength and the conditions of time and temperature employed for the sulfonation should be such as to permit only partial sulfonation, for example sulfonation of from, say, 30 per cent to 80 per cent of the xylene fraction, depending upon the meta-xylene content of the fraction.

The present process is suitably employed for the recovery of para-xylene and of the ethylbenzene from technical xylenes of varying compositions containing preponderant quantities of meta-xylene and para-xylene together with lesser quantities of ortho-xylene and ethylbenzene.

What I claim is:

1. In a process for the recovery of para-xylene from technical xylene, the steps which include partially sulfonating said xylene, removing unsulfonated oil from the partially sulfonated product, fractionally hydrolyzing the residue at a temperature of up to 120° C., bringing together the hydrolyzed fraction with the unsulfonated oil, completely sulfonating the resulting mixture and fractionally hydrolyzing the completely sulfonated material to obtain a predominantly para-xylene-containing fraction.

2. In a process for the recovery of para-xylene from technical xylene, the steps which include partially sulfonating said xylene, removing unsulfonated oil from the partially sulfonated product, fractionally hydrolyzing the residue to obtain a first hydrolyzed product boiling at a temperature of up to 120° C. and a second hydrolyzed product boiling above a temperature of 145° C., adding the first and the second hydrolyzed products to said unsulfonated oil, completely sulfonating the resulting mixture and fractionally hydrolyzing the completely sulfonated material to obtain a predominantly p-xylene-containing fraction.

3. In a process for the recovery of para-xylene and of ethylbenzene from technical xylene, the steps which include partially sulfonating said xylene, removing unsulfonated oil from the partially sulfonated product, fractionally hydrolyzing the residue to obtain a hydrolyzed product boiling up to a temperature of 120° C., bringing together the hydrolyzed product with the unsulfonated oil, completely sulfonating the resulting mixture, and fractionally hydrolyzing the completely sulfonated material to obtain a predominantly para-xylene-containing fraction and a predominantly ethylbenzene-containing fraction.

4. In a process for the recovery of para-xylene and of ethylbenzene from technical xylene, the steps which include partially sulfonating said xylene, removing unsulfonated oil from the partially sulfonated product, fractionally hydrolyzing the residue to obtain a first hydrolyzed product boiling at a temperature of up to 120° C. and a second hydrolyzed product boiling at a temperature of over 145° C., adding the first and second hydrolyzed products to said unsulfonated oil, completely sulfonating the resulting mixture, and fractionally hydrolyzing the resulting material to obtain a predominantly para-xylene-containing fraction and a predominantly ethylbenzene-containing fraction.

5. A process for the recovery of para-xylene and ethylbenzene from technical xylene containing major proportions of meta-xylene and of para-xylene and minor proportions of ortho-xylene and of ethylbenzene which comprises reacting said technical xylene with sulfuric acid under conditions permitting only partial sulfonation of the technical xylene, removing unsulfonated oil from the resulting reaction mixture, diluting the residue with water, distilling the diluted material to obtain a forerun boiling up to a temperature of approximately 120° C., an intermediate hydrolysis fraction boiling at a temperature of from 120° C. to 145° C. and another hydrolysis product boiling above 145° C., adding said forerun and the last hydrolysis product to the unsulfonated oil, treating the resulting mixture with sulfuric acid for a complete sulfonation

of said mixture, diluting the completely sulfonated material with water, distilling the diluted material to obtain a predominantly para-xylene-containing fraction boiling between a temperature of from 150° C. to 170° C. and a predominantly ethylbenzene-containing fraction boiling above 170° C.

6. A process for the recovery of para-xylene and ethylbenzene from technical xylene containing major proportions of meta-xylene and of para-xylene and minor proportions of ortho-xylene and of ethylbenzene which comprises reacting said technical xylene with sulfuric acid under conditions permitting only partial sulfonation of the technical xylene, removing unsulfonated oil from the resulting reaction mixture, diluting the residue with water, distilling the diluted material to obtain a forerun boiling up to a temperature of approximately 120° C., an intermediate hydrolysis fraction boiling at a temperature of from 120° C. to 145° C. and another hydrolysis product boiling above 145° C., adding said forerun and the last hydrolysis product to the unsulfonated oil, treating the resulting mixture with sulfuric acid for complete sulfonation of said mixture, diluting the completely sulfonated material with water, distilling the diluted material to obtain a predominantly para-xylene-containing fraction boiling between a temperature of from 150° C. to 170° C. and a predominantly ethylbenzene-containing fraction boiling above 170° C., cooling the fraction which boils at a temperature of from 150° C. to 170° C. to solidify para-xylene and filtering the solidified para-xylene from the cooled fraction.

7. A process for the recovery of para-xylene and ethylbenzene from technical xylene containing major proportions of meta-xylene and of para-xylene and minor proportions of ortho-xylene and of ethylbenzene which comprises reacting said technical xylene with sulfuric acid of less than 95 per cent H₂SO₄ concentration under conditions permitting only partial sulfonation of the technical xylene, removing unsulfonated oil from the resulting reaction mixture, diluting the residue with water, distilling the diluted material to obtain a forerun boiling up to a temperature of approximately 120° C., an intermediate hydrolysis fraction boiling at a temperature of from 120° C. to 145° C. and another hydrolysis product boiling above 145° C., adding said forerun and the last hydrolysis product to the unsulfonated oil, treating the resulting mixture with sulfuric acid of greater than 95 per cent concentration for complete sulfonation of said mixture, diluting the completely sulfonated material with water, distilling the diluted material to obtain a predominantly para-xylene-containing fraction boiling between a temperature of from 150° C. to 170° C. and a predominantly ethylbenzene-containing fraction boiling above 170° C.
